UNITED STATES PATENT OFFICE.

GEORGE H. HIGGINS, OF GRAND RAPIDS, MICHIGAN.

ROBE-RACK.

1,233,576.

Specification of Letters Patent. Patented July 17, 1917.

Application filed January 5, 1916. Serial No. 70,519.

To all whom it may concern:

Be it known that I, GEORGE H. HIGGINS, a citizen of the United States, residing at Grand Rapids, in the county of Kent and State of Michigan, have invented certain new and useful Improvements in Robe-Racks; and I do hereby declare the following to be a full, clear, and exact description of the invention, such as will enable others skilled in the art to which it appertains to make and use the same.

The primary object of this invention is to improve the construction of racks, designed to be mounted on the rear sides of the back of automobile seats, so as to hold robes and similar apparel, by providing a rack formed of companion clamping sections adapted to clamp the robes therebetween, and having means associated therewith for positively holding the clamping members in clamping position.

Another object of the invention is to provide a rack for carrying out the above object, and so constructed that the clamping members can have relative adjustment so as to accommodate robes of different thicknesses.

A further object of this invention is to provide a rack of this nature that will be of simple construction, cheap to manufacture, will be durable and efficient in operation, and will admit of the robes or other articles, being clamped or unclamped expeditiously.

Other objects will appear and be better understood from that embodiment of my invention of which the following is a specification, reference being had to the accompanying drawings forming a part thereof, in which:—

Figure 1 is a view showing the improved rack applied to the rear side of the back of the front seat.

Fig. 2 is a front view of the rack, removed from the seat back, and showing the opposite ends of one of the clamping members in section.

Fig. 3 is a section taken on the line 3—3 of Fig. 2.

Fig. 4 is a detail section taken through one end of one of the clamping members and showing the locking means for holding the clamping members in operative position.

Fig. 5 is a front view of a modified form of rack.

Fig. 6 is a section taken on the line 5—5 of Fig. 5.

Referring to the drawing, the letter A designates an automobile body, as an entirety, and B the back for the front seat. Positioned on the rear side of the back B, is a pair of brackets which are spaced from each other and which include the base plates 1 and 2 secured to the back B, by means of the fastening elements 3, the said plates 1 and 2 having arms 4 projecting outwardly therefrom and having the free ends of the arms formed to provide semicircular seats 6. Associated with the outer ends of the arms 4, are semi-cylindrical caps 7, which overlie the seat 6 and form therewith sleeves as shown in Fig. 3 of the drawings.

An elongated clamping rod 8 is received by the sleeve, and has its opposite ends extending beyond the outer ends of the sleeves as shown at 9 and 10 and terminally provided with the knobs 11 and 12. The rod 8 is provided, at points between the outer ends of the sleeve and the knobs 11 and 12, with transversely extending openings 13 and 14, and the said rod has formed thereon, a plurality of spaced conically shaped fingers 15, certain of the fingers lying on opposite sides of the sleeves, so as to prevent longitudinal movement of the rod through the sleeves.

The companion clamping rod 16, is arranged in parallelism with the clamping rod 8 and has its opposite terminal provided with heads 17, and 18. The rod 16 is provided at points adjacent its opposite ends with transverse openings 19 and 20, which are arranged in alignment with the openings 13 and 14 in the clamping rod 8. The rod 16 has also formed thereon, a plurality of laterally projecting conical shaped fingers 21, which extend in the direction of the rod 8, and are aligned with the spaces between the fingers 15 formed on the rod 8 as is clearly shown in Fig. 2 of the drawings.

The bars 8 and 16 have adjustable connection with each other, by means of connecting links 22 and 23. Each of these links 22 and 23 has one end pivoted as at 24, within one of the openings in the rod 8 and has its opposite end slidably extending through the openings in the adjacent end of the rod 16. Each of the links 22 and 23 has one side

thereof provided with rack teeth 25, adapted to be interchangeably engaged by a sliding lock bar 26, slidale through the adjacent end of the clamping bar 16 and adapted to be operated in the ordinary manner, by means of a key inserted within a key hole 27 formed in the adjacent end of the clamping bar 16. By virtue of the links 22 and 23, having the rack teeth 25 formed thereon, and the slideable locking bar 26, the clamping bar 16 can be adjusted toward or away from the clamping bar 8, so as to accommodate robes of different thicknesses.

In the modifications shown in Figs. 5 and 15 6, the clamping bars 8 and 16 have connection with each other by means of a pair of links 28 and 29, which are located at one 20 end of the rack, and on opposite sides of the adjacent ends of the clamping bars 8 and 16. This construction admits of the clamping bar 16 having swinging movement so as to allow the robes, or other articles, to be expeditiously positioned between the clamping bars 8 and 16. In the construction of 25 25 rack shown in Figs. 5 and 6, the clamping bar 8 is shown provided with an arcuate shaped rack bar 30 designed to be received by the opening in the adjacent end of the bar 16, the said bars being adapted to be 30 locked in operative position by a sliding lock bolt, similar to the one shown at 26 in Fig. 4 of the drawings.

The clamping rod 8 shown both in the preferred and the modified form of construction, is adapted to have rotary movement within the sleeves and the brackets so that when it is desired to clamp the robe or other articles between the rods 8 and 16, the rod 16 can be swung downwardly, as shown in 40 Fig. 6 and then moved to open position so that the article can be conveniently placed between the clamping rods 8 and 16. The fingers 15 and 21 are adapted to engage the article clamped, and by virtue of their arrangement the fingers on one clamping rod will force portions of the article clamped between the fingers on the other clamping rod, and in this way assure a maximum clamping action for the article. 45 50 The fingers 15 and 21 are provided with rubber tips 32, so that the gripping efficiency of the fingers will be maximized. When positioning a robe, or other article, between the bars 8 and 16, shown in Fig. 1, the bar 55 16 may be removed entirely from the links 22 and 23, or, if desired, only one end of the bar 16 may be detached from the adjacent link, and the bar 16 swung to unclamping

position on the other link, similar to the bar 16, shown in Fig. 5 of the drawings.

Having thus described my invention what I claim as new is:

1. A rack of the class described comprising, a clamping bar, a second clamping bar positioned in spaced relation to the first-mentioned clamping bar and pivoted for movement toward and away from the first bar, the said second bar having an opening therein, a pivoted element carried by the first-mentioned bar and adapted to be received by the opening in the second-mentioned bar when the clamping bars are in operative position, the said pivoted element having a plurality of teeth thereon, and means for operatively engaging certain of the teeth on the pivoted element when the said element is received by the opening in the second-mentioned bar, so as to hold the clamping members in clamping position.

2. A rack of the class described comprising companion clamping bars, one of the bars having openings therein, laterally extending links pivotally associated with the other clamping bar and slideable through the opening in the first-mentioned bar so as to adjustably connect the first-mentioned bar to the second-mentioned bar, the said links having teeth thereon, and means carried by the first-mentioned bar for interchangeably engaging in the teeth on the links for holding the first-mentioned bar in adjusted and clamping position.

3. A device of the class described comprising a rotatably mounted clamping bar, a second clamping bar, links connecting the second clamping bar to the first bar so as to admit of the second bar having movement toward and away from the first bar, the said second bar having an opening therein, a rack bar pivotally mounted on the first bar and extending in the direction of the second bar and adapted to be received by the opening in the second bar when the latter bar is moved toward the first bar, and means carried by the second bar for engaging in the teeth on the rack when the rack bar is received by the opening in the second bar, so as to hold the second bar against movement.

In testimony whereof I affix my signature in presence of two witnesses.

GEORGE H. HIGGINS.
